(57) **CLAIM**

The ornamental design for a container with viewing window, as shown and described.

DESCRIPTION

FIG. 1 is a perspective view of a first embodiment of a container with viewing window showing our new design;

FIG. 2 is a front elevational view thereof;

FIG. 3 is a left side elevational view thereof, the right side being identical thereto;

FIG. 4 is a top plan view thereof;

FIG. 5 is a rear elevational view thereof;

FIG. 6 is a perspective view of a second embodiment of a container with viewing window showing our new design;

FIG. 7 is a front elevational view thereof; and,

FIG. 8 is a rear elevational view thereof.

The broken line showing of a container dispenser in FIGS. 1–8 is included for the purpose of illustrating only and forms no part of the claimed invention.

All sides not shown form no part of the claimed design.
